Search Report from corresponding Taiwan Application No. 102305782, completed on Aug. 25, 2014.

Primary Examiner — Paula Greene(74) *Attorney, Agent, or Firm* — Renner, Otto, Boisselle & Sklar, LLP(57) **CLAIM**

The ornamental design for a headset, as shown and described.

DESCRIPTION

FIG. 1 is a perspective view of a neckpiece component of a headset, showing my new design.

FIG. 2 is another perspective view thereof.

FIG. 3 is a front view thereof.

FIG. 4 is a rear view thereof.

FIG. 5 is a top view thereof.

FIG. 6 is a bottom view thereof.

FIG. 7 is a right side view thereof; and,

FIG. 8 is a left side view thereof.

The broken lines shown herein are for illustrative purposes only and form no part of the claimed design.
